UNITED STATES PATENT OFFICE.

WALTER H. LYMAN, OF CHICAGO, ILLINOIS, ASSIGNOR TO THE AMERICAN PERFORATOR COMPANY, OF CHICAGO, ILLINOIS, A CORPORATION OF ILLINOIS.

CRYPTOGRAPHIC PERFORATOR.

Application filed December 11, 1924. Serial No. 755,183.

My invention relates to cryptographic perforators.

One of the objects of my invention is to provide a cryptographic perforator which 5 will enable the use of a smaller number of punches and a smaller size of selector wheel than have heretofore been used.

A further object of my invention is to provide a cryptographic perforator which will 10 produce a simplified cryptogram.

Further objects will appear from the description and claim.

My invention is in the nature of an improvement of the inventions disclosed in patents to Day, No. 739,398 and No. 739,399. 15 The Day Patent No. 739,399 shows a cryptographic perforator in which numbers from one up to one hundred may be indicated by the use of 11 punches and a pair of overlapping selector wheels, each having fifteen selector faces. By my improved perforator, I 20 accomplish a similar result using only eight punches and a pair of overlapping selector wheels, each of which may have only 10 selector faces. Furthermore, the cryptogram made by my improved perforator is simpler than the cryptogram made by the perforators of the patents referred to, and the operation 25 of my improved perforator is simpler than the operation of the perforators of the 30 patents referred to. This simplification is accomplished by a method of indicating the desired number, which method comprises making base perforations in the sheet, assigning 35 certain numbers to perforable parts of the sheet, which parts have definite positions with respect to the base perforations, and perforating a plurality of such spaces in such manner that the sum of the numbers allotted 40 to the perforated spaces equals the desired number.

In the drawings, in which my invention is illustrated—

Figure 1 is a transverse vertical section 45 through a perforator on the line 1—1 of Fig. 2;

Fig. 2 is a longitudinal vertical section through the perforator on the line 2—2 of Fig. 1;

Fig. 3 is a development view showing the 50 four selector wheels straightened out;

Fig. 4 is a view showing the arrangement of the punches; and

Fig. 5 is a view showing perforations 55 which indicate a date (April 6, 1924).

Referring to the drawings in detail, and first to the arrangement and assigned valuation of the punches shown in Fig. 4, this arrangement is intended primarily for making cryptograms to indicate dates, that is, 60 months, days and years, although it can just as effectively be utilized for marking numbers or a combination of both, as can be readily appreciated. The section lined circles indicate the base punches, all four of 65 which are operated whenever the date is punched. The eight punches to the left of the left hand pair of base punches are used to indicate the number of the month. The 70 eight punches between the two pairs of base punches are used to indicate the day of the month. The eight punches at the right of the right hand pair of base punches are used to indicate the number of the year. The 75 numbers within the various circles indicating the punches, show the number or value which is assigned to each particular punch.

The various groups of punches shown are so controlled by the selector wheels that the 80 sum of the numbers punched in each group is equal to the desired number. To illustrate, if it is desired to make a perforated cryptogram which will indicate April 6, 1924, the selector wheels are so set that in the "month" 85 group of perforations, only the "4" punch will be operated; so that in the "day" group of punches the punches "2" and "4" will be operated; and so that in the "year" group of punches, the punches "4" and "20" will 90 be operated. This cryptogram is shown in Fig. 5, in which the base perforations in the sheet are indicated by circles with section lines and the significant perforations are indicated by circles surrounding figures. The month perforation to the left of the left hand 95 pair of base perforations, numbered 4 indicates April. The two perforations between the two pairs of base perforations added together equal 6, indicating the sixth day of the month. The two perforations to the 100 right of the right hand pair of base perforations added together equal 24 indicating the year 1924. It will be found that the punches with numbers assigned as indicated enable a selection to be made corresponding to any 105 desired number between 1 and 100.

Referring now to the construction of the perforator used in making these cryptograms, this comprises a group of punches 10, an oscillatable head 11, and four selector 110

wheels 12, 13, 14 and 15 rotatably mounted on the head 11 for controlling the punches 10. Each of these selector wheels is provided with a series of groups of perforations for cooperation with the punches. If one of the selector wheels is turned so that a certain group of perforations is brought just above the upper ends of the group of punches controlled by that selector wheel 10 and the punch head is then operated, certain of the punches will be received in the perforations in the selector wheel and the punches thus received will not be depressed and hence will not cause any corresponding 15 perforation in the sheet operated on. The rest of the punches in the group controlled by this selector wheel will be depressed as there are no perforations in the selector wheel to receive them and these punches 20 which are depressed will cause corresponding perforations in the sheet.

Means are provided whereby the operator can set all four of the selector wheels at any desired position comprising a plurality 25 of readily insertable and withdrawable pins 16, one for each selector wheel, which can be inserted into properly spaced holes in the selector wheels, the pin being then used as a handle to rotate the selector wheel. In 30 order to definitely position the selector wheels with respect to the punch head, the latter is provided with a transversely extending groove 17 into which the controlling pins can be inserted when the wheels have 35 been moved to bring the pins opposite the groove.

The sheet to be perforated is inserted between the perforated platen 18 and the lower 40 ends of the punches. In order to return the punches after they have been depressed, a perforated lifter plate 19 is provided through which the punches extend. This lifter plate is elevated on the upward stroke of the punch made by means of a pair of 45 hooks 20 secured to the punch head and extending underneath the lifter plate. The punches are provided with enlargements or shoulders 21 engaged by the lifter plate. Any suitable type of handle 22 may be provided 50 for operating the punch member which is returned by a coil compression spring 23.

Referring now more particularly to the construction of the selector wheels which 55 are shown in Fig. 3, the left hand wheel 12 used to indicate the month has 12 groups of perforations, one for each month. Each of the perforations 24 into which the control pins may be inserted is provided with a number 60 at the right to enable the operator to select the right group of punches. This number does not of course correspond to the immediately adjacent group of perforations because of the fact that the perforation 24 65 for the controlling pin must be located about

120° from the group of perforations which correspond to it. The reason for this 120° spacing will be obvious by referring to Fig. 2, which shows that the groove 17 in the punch head, which receives the controlling 70 pin, is about 120° from the groove 25 which receives the upper ends of the punches. The numbers appearing just to the right of the perforations which receive the control pin (Fig. 3) are the numbers which are 75 actually placed on the selector wheel, but the numbers in parenthesis in the column just to the right of the selector wheel are the numbers which actually correspond to the adjacent group of holes. Thus, the upper 80 group of holes in the left hand selector wheel, shown in Fig. 3, correspond to No. 9. The full circles in each group indicate actual perforations in the wheel so that the punches corresponding to these perforations 85 will not be operated. The semi-circles in each group indicate that this part of the wheel is not perforated. As a matter of fact, the parts of the wheel indicated by the semi-circles are provided with slight depressions or pockets 26 (Fig. 1) for the purpose of receiving and centering the upper 90 ends of the punches when the punch head is depressed. The punches corresponding to these semi-circles will be operated. Referring again, particularly, to the upper group 95 of perforations in the left hand selector wheel, it will be noted by referring to Fig. 4 that the three semi-circles correspond to the Figs. 2, 3 and 4. The sum of these figures 100 is 9, which is the desired number for this group. In order to avoid confusion it is here pointed out that the arrangement of 105 perforations in the selector wheel shown in Fig. 3 appears inverted with respect to the arrangement of perforations shown in Fig. 4. For another example of the arrangement 110 in the left hand selector wheel, consider the fourth group of perforations from the top, corresponding to the number 12, which appears in parenthesis at the right. By referring to Fig. 4, it will be seen that two semi-circles in the group under consideration, 115 correspond to numbers 10 and 2, the sum of which is 12.

The right hand selector wheel is similar in principle and operation to the one just described. The figures in parenthesis in the column at the right of the upper end of this selector wheel indicate the value corresponding to the different groups of perforations. Thus, for the upper group the value is the sum of 30 and 2 or 32, etc.

This selector wheel with its 12 groups of 120 perforations enables any desired year to be indicated from 1924 to 1935.

A greater range of numbers is necessary for indicating the day of the month than is necessary for indicating the month or year, and I accordingly find it convenient to pro- 130

vide two overlapping selector wheels for controlling the "day" punches. These selector wheels have overlapping portions, both of which overlapping portions are provided with groups of perforations so that any particular punch will be depressed unless there are corresponding perforations to receive it in both of the selector wheels. I arrange the perforations in these two selector wheels so that the left hand selector wheel controls the punches indicated as 10, 20, 30 and 40 in Fig. 4 and so that the right hand selector wheel controls the punches indicated as 1, 2, 3 and 4 in Fig. 4. The left hand selector wheel is thus in effect a "tens" wheel while the right hand selector wheel is a "units" wheel. Assume for instance that it is desired to indicate the 26th day of the month. The control pin for the "tens" wheel is inserted in the control pin opening marked "20" and the wheel is moved until the control pin can be slipped into the notch in the punch head. The control pin for the units wheel is inserted into the control pin opening marked "6" and this selector wheel also is turned until its control pin can be inserted in the groove in the punch head. This will bring the group of punch controlling openings marked "20" in the "tens" wheel to be brought just above the upper ends of the punches and will bring the group of the punch controlling openings marked "6" in the units wheel just above the punches. The punch controlling group marked "20" will cause the actuation of a single punch corresponding to the single half circle which corresponds to the number "20." The other seven punches in the "day" group will pass through the openings in the "tens" or selector wheel but two of these will be engaged by the units selector wheel, causing the punches which indicate "2" and "4" to be operated. Thus altogether 3 punches will be operated by means of the two selector wheels and the sum of the corresponding numbers will be "26."

Attention is called to the fact that some of the punches could be eliminated so far as merely dating perforations are concerned.

For instance, in the group of punches for

indicating the number of the month, the punches corresponding to 20, 30 and 40 could be eliminated. In the group of punches for indicating the day of the month, the punch corresponding to No. 40 could be omitted and by combining the punches corresponding to 10 and 20 to make 30 both punches 30 and 40 could be omitted. In the group of punches for indicating the year, the punch corresponding to 40 could be omitted as there is no corresponding pin receiving opening in the selector wheel. Furthermore, by combining the punches 10 and 20, both of the punches corresponding to 30 and 40 could be omitted. This would enable the dating to be done by the use of only 17 punches. It will be seen that the present construction is considerably simpler than the construction shown in the prior patents referred to in that a much smaller number of punches may be used and also a smaller number of faces or groups of punch controlling openings in the selector wheels.

Having thus described my invention, what I claim as new and desire to secure by Letters Patent of the U. S. is:—

A cryptographic perforating machine comprising base punches, which when operated punch base perforations in a sheet, a group of spaced significant punches, each of which when operated, makes a perforation in the sheet having a definite relative position with respect to a base perforation, to which relative position a definite number is assigned, and a series of selective devices for controlling said punches, any one of which devices may be selected by the operator to control the punches to cause them to indicate a desired number, each of a number of said selective devices comprising means for causing the operation of the base punches, and comprising also means for causing the operation of a plurality of additional punches to make significant perforations, the sum of whose corresponding numbers equals the desired number.

In witness whereof, I have hereunto subscribed my name.

WALTER H. LYMAN.
